Primary Examiner — Jonathan J Han(74) *Attorney, Agent, or Firm* — Woodard, Emhardt, Henry, Reeves & Wagner, LLP(57) **CLAIM**

The ornamental design for a firearm receiver, as shown and described.

DESCRIPTION

FIG. 1 is a first perspective view of the a firearm receiver showing our new design;

FIG. 2 is a second perspective view thereof;

FIG. 3 is a third perspective view thereof;

FIG. 4 is a fourth perspective view thereof;

FIG. 5 is a right side view thereof;

FIG. 6 is a left side view thereof;

FIG. 7 is a front end view thereof;

FIG. 8 is a rear end view thereof;

FIG. 9 is a top view thereof; and,

FIG. 10 is a bottom view thereof.

The broken lines illustrate portions of the firearm receiver that form no part of the claimed design.

1 Claim, 4 Drawing Sheets(56)
